VOLUME CONTROL

Application filed March 11, 1929. Serial No. 348,112.

This invention relates to volume control for radio sets, public address systems, and the like, more particularly to a volume control which exercises a control over the circuit at more than one point in the circuit.

In order to control the volume of a radio set it has become the practice to insert a variable resistor in multiple with one of the windings of a transformer in the radio set. 10 This control may be exercised at the beginning of the circuit through the set, that is adjacent to the antenna or pick-up device through which radio signals are received in the set, or in some instances it may be exercised at a point adjacent to the detector tube of the set.

Often times the resistor takes the form of a potentiometer or potential divider in that a fixed resistance is connected across the 20 winding of the transformer at the point to be controlled and the antenna is connected to the variable arm of the potentiometer, the volume being controlled by varying the position of this arm with respect to the fixed resistance.

In the modern radio sets in which incoming signals are amplified through a plurality of stages of radio frequency amplification before being impressed upon the elements of 30 the detector tube, it is often times difficult to properly control the volume of the set by the application of a resistor or potentiometer at one point in the set. This condition has led to the use of the so-called gang volume control in which two or more potentiometers or resistors are inserted in the radio circuit and operated to control the volume at more than one point. For example, the antenna may be coupled to the first tube through a resistor 35 or, and the last radio frequency amplifier may be coupled to the detector through a second resistor. These two resistors are usually connected together mechanically and operated simultaneously by a single dial or 40 knob mounted on the panel.

The present invention relates to volume control devices of this latter type, in which two or more electrically and mechanically independent resistor or potentiometer units are mounted in line and controlled through 50 the operation of a single knob or dial.

Volume control devices of this type may be made in any one of several forms, that is all of the electrical circuits of the one unit may be insulated from and independent of 55 the electrical circuit of the other units, or a part of these two circuits may be commoned, and the commoned circuit may be connected to the ground.

Multiple unit devices of this kind operated 60 by a single shaft are not limited to the control of volume in a radio set, a public address system, or the like, as by suitable choice of resistance value and current carrying capacity the devices may be put to a plurality 65 of uses such as balancing out the hum in an alternating current power pack, or as a filament rheostat to control the temperature of a filament of a vacuum tube.

My invention, while it is shown applied to 70 a plurality of resistance units coupled together, is equally applicable to a plurality of inductance units, or a plurality of condensers such as might be used to control feed backs or regeneration in a radio receiver.

The present invention provides an improvement in supporting and coupling two rheostats or control units so that they may be operated in unison for joint control of an 80 electric circuit or device. In the manufacture of such combined or combination units in quantity, unavoidable slight errors in alignment of the parts may occur and it is the object of my present invention to make 85 provision for securing a relatively high degree of accuracy of joint movement and smoothness of operation under the aforesaid conditions of manufacture.

Now in order to acquaint those skilled in 90

the art with the manner of constructing and operating a device embodying my invention I shall describe in connection with the accompanying drawings a specific but optional form of the same.

In the drawings:

Figure 1 is a plan view of an embodiment of the invention;

Figure 2 is a section view of Figure 1, taken along the line 2—2 looking in the direction of the arrows;

Figure 3 is a cross-section view of Figure 1, cut along a middle vertical plane; and

Figure 4 is a circuit diagram illustrating one application of the devices of the invention.

In the embodiment herein illustrated the units 60 and 61 are mounted on a common U-shape frame member 62 and controlled by a single knob 87. The unit 60 is mounted on an insulating member 63 which is riveted to the open end of the U-frame 62, and which serves to insulate the unit 60 from the frame. The insulating plate 63 having the rheostat 60 secured by the clamping nut 86 and hub 84 to its central part and having its edges secured to the frame 62, acts like a diaphragm to the extent of providing for a limited amount of freedom of self-alignment, axially and angularly, of the unit 60. Unit 61 is mounted upon the mid-section of the frame 62, being insulated therefrom by the washers 77, 79, and 80. The unit 61 comprises the tubular sleeve member 75 having a reduced threaded neck extending through a hole in the central part of the frame 62. This neck is threaded to receive the clamping nut 76. The entire device may be mounted by extending the threaded neck of the sleeve member 75 through a hole in a panel or the like and screwing up the nut 76. The shaft 74 has a shoulder which bears endwise against the outer end of the threaded neck. On its inner end the shaft 74 has the collar 71' secured thereto as by a setscrew as shown in Figure 2, and between said collar 71' and the sleeve 75 a spring washer 75' is interposed. The unit 60 likewise has its shaft 81 journaled in a sleeve member 84 and restrained against axial displacement by a head formed at the left end of the shaft 81 which head has a shoulder resting against the end of the threaded part of the collar 82 and a spring washer 82' between the collar 82 and the sleeve 84. A flexible coupling 70 of insulating material connects the shaft 74 of the unit 61 to the shaft 81 of the unit 60. The flexibility of the coupling 70 and the flexibility of the mounting of 63 of unit 60 aids in the alignment of the shaft 81 with respect to the shaft 74 to insure smooth easy operation of the device. The resistor unit 61 comprises the cuplike metallic body 72 around the outside of which the resistance unit 65 is placed.

The resistance unit 65 comprises the insulator strip 65' around which is wound the resistance wire 65. The resistance unit 65 is insulated from the frame 72 by the insulating strip 87, which is placed around the outside edge of the body 72 between it and the resistor. The ends of the resistance unit are connected to terminals. The bushing 75 is provided with a collar which engages the edges of an opening in the body 72, and also provided with a thread upon which the nut 76 is threaded to mount the unit upon the support 62.

The shaft 74 to which the knob 87 is attached is provided with a collar which rests against the end of the bushing 75, and the shank which projects through the opening in the bushing 75 on which shank the collar 71' carrying the contact member 71 is attached by a set screw or other suitable means. A spring washer 75' is interposed between the inside edge of the bushing 75 and the collar 71' to keep the shoulder of the shaft 74 firmly against the end of the bushing 75. A slot 70' is cut in the end of the collar 71' into which slot the insulator coupling 70 is fitted. The opposite end of the coupling 70 is fitted into a similar slot in the collar 82 which is mounted on the shaft 81 of the unit 60 and which carries the contacting member of the unit 60. The plate 70 which forms the coupling is notched at its opposite ends to clear the adjacent ends of the shafts 74 and 81, which ends may vary slightly as to their position with respect to the hubs or collars 82 and 71'. This plate has integral portions comprising ears extending into narrow parallel sided slots formed in said hubs diametrically disposed on opposite sides of the shaft ends. The plate 70 is further provided with ears extending over the outside surfaces of the hubs 82 and 71' to prevent edgewise diametrical displacement of the plate 70 with respect to either hub. Obviously, the edges of the plate 70 should have sufficient clearance to produce the desired degree of universal motion which it is the object of the plate 70 to accomplish.

The ears which extend over the outer surfaces of the hubs do not rest in notches but merely extend axially along the cylindrical surface of the hubs 82 and 71' and are free to play sidewise over such cylindrical surfaces. The use of these latter ears is optional.

By the above arrangement of the plates resting in the notches and held in place against edgewise motion diametrically of the shaft, a limited degree of universal motion is provided in the coupling between the two shafts to take care of such unavoidable deviations from axial alignment as are encountered in quantity production. While the coupling is inexpensive and easily constructed and assembled, it is surprisingly effective for the transmission of considerable torque and

for taking up such small lack of alignment as occurs in quantity production of the units. It holds the two shafts together for rotary or angular motion with very little play and at the same time permits of the transmission of a considerable torque. The construction of the unit 60 being identical with that of 61 need not be described in detail at this time.

10 The mounting 63, which is preferably made of bakelite or a similar phenol condensation product, is slightly flexible and permits limited movement of the resistor unit 61. The flexible coupling 70 which fits into the slot 70' in the collars 71' and 82, keys the two 15 units together so that when the knob 87 is rotated the contacting member of both units are moved over the resistance element.

15 Since the coupling member 70 is an insulator the two units are insulated from each 20 other electrically, and more over are insulated from the frame member 72 which may be mounted upon a conducting panel. As 25 illustrated, the units 60 and 61 are potentiometers although simple resistance elements may be substituted if desired.

25 In Figure 4, I show one of the many adaptations of my invention in an electrical circuit. For the purpose of illustration, I have shown a portion of a radio circuit in which the antenna A is coupled to the first radio frequency transformer T1 by the potentiometer 60. The antenna is connected to the variable arm of the potentiometer and the ends of the resistor are connected to the opposite ends 35 of the primary winding of transformer T1. Signals picked up by the antenna are amplified through the transformers T1, T2, and T3 and the tubes B1, and B2 before being impressed on the grid of the detector tube B3.

40 The resistor of potentiometer 61 is connected between the plate of the tube B2 and battery and the rider of 61 is connected to the one terminal of the primary winding of the transformer T3.

45 By the arrangement of the potentiometers 60 and 61, the input and output of the radio frequency amplifier are regulated to control the volume. This arrangement does not alter the tuning of the set by adjustment of condensers C, C2, and C3. Obviously the variable arms or riders of units 60 and 61 must be insulated from each other and from ground.

55 The units may be inductances or condensers if desired without departing from the teachings of my invention.

Having thus complied with the statutes and shown and described a preferred embodiment of my invention, what I consider new and desire to have protected by Letters Patent is pointed out in the appended claims.

What is claimed is:—

1. In a volume control, a resistance unit comprising a base, a resistance element attached to one side of said base and insulated

therefrom, a rider movably engaging said resistance unit, a shaft for moving said rider, a mounting frame from which said base is insulated, a second and similar resistance unit, flexible means for mounting said second unit on said frame with its shaft in substantial alignment with the shaft of the first unit, and a coupling between said shafts through which the rider of said second unit is moved by a movement of the rider of the first. 70

2. In combination, a resistance unit comprising a base, a resistance element attached to one side of said base and insulated therefrom, a rider movably engaging said resistance unit, a shaft for moving said rider, a hub for mounting the rider on the shaft, a pair of radial slots in said hub, a mounting frame upon which said unit is mounted and from which said base is insulated, a second and similar resistance unit, insulating means 80 for mounting said second unit on said frame with its resistance element adjacent the element of the first unit and with its shaft in alignment with the shaft of the first unit, and a coupling of insulating material between 85 said shafts and having tongues engaging said hub slots through which the rider of said second unit is moved by a movement of the rider of the first. 90

3. The combination of a plurality of electrical control devices, a shaft in each device, a mounting therefor, said mounting rigidly supporting one of said devices and flexibly supporting another with the shafts of the two in substantial alignment, a coupling between adjacent ends of said shafts, and a knob for simultaneously adjusting said shafts to adjust said devices. 95

4. In combination, a pair of electrical circuit controlling devices having operating 105 shafts journaled for rotation and possessing a limited degree of endwise freedom; means for mounting said devices with the shafts adjacent to each other and in approximate alignment, contact arms possessing hub members on said shaft ends, said hub members having substantially diametrically disposed parallel sided slots, and a coupling member comprising a plate provided with pairs of ears at each end, said ears extending into 110 said slots and coupling the contact arms together for rotary motion with a limited degree of universal freedom. 115

5. In combination, a pair of rheostats each having a frame member with a circularly disposed resistance element, and a shaft member disposed substantially axially with respect to its resistance element and having a radially extending contact arm possessing a hub member on the shaft, each shaft being angularly movable for changing location of contact along the resistance element, means for connecting said frame members together with the shafts substantially in alignment and with the hub members adjacent each other, 120 125 130

said hub members having parallel sided, diametrically disposed slots, and a flat plate having a pair of spaced ears at each end entering the slots and forming, in conjunction with the slots, a universal coupling between the contact arms.

6. In combination, a pair of rheostats each having a frame member with a circularly disposed resistance element, and a shaft member disposed substantially axially with respect to its resistance element and having a radially extending contact arm possessing a hub member on the shaft, each shaft being angularly movable for changing location of contact along the resistance element, means for connecting said frame members, with the shafts substantially in alignment and with the hub members adjacent each other, said hub members having relatively narrow, diametrically disposed, parallel sided slots, and a flat plate of insulation having its opposite ends extending into the slots and forming, in conjunction with the slots, a universal coupling between the contact arms, said plate and hubs having interacting shoulders for preventing radial displacement of the plate with respect to the slots.

7. In combination, a frame member, a rheostat having a base mounted on the frame member, said rheostat having an operating shaft, a second rheostat having a base and also having a shaft, a thin, flexible plate having its edges only secured to the frame member and having its central part only connected to the base of the second rheostat, the shafts of the two rheostats being substantially in alignment and having their ends adjacent each other, and a coupling having a limited freedom for universal motion connecting the contact arms on the ends of the shafts.

8. In combination, a pair of rheostats comprising bases which are connected together, circularly disposed resistance elements mounted on said bases, shafts journaled in said bases substantially in axial alignment, movable contact arms for engaging the rheostats, said contact arms having hub members which are mounted on the adjacent ends of the shafts, said hub members being provided with substantially diametrically disposed slots, and a coupling plate having pairs of projections entering said slots and coupling the hubs together for rotary motion, said projections providing shoulders for limiting radial displacement of the plate with respect to the connected shafts.

9. In combination, a pair of rheostats having bases connected together, circularly disposed resistance elements on said bases, said rheostats having rotatably mounted shafts provided with contact controlling arms cooperating with said elements, said arms having hubs provided with narrow, diametrically disposed slots, said shafts being mounted

end to end substantially in axial alignment, with the aforesaid hubs adjacent each other, and a flat coupling plate disposed between the ends of the shafts, said plate having a pair of ears at each end projecting into the corresponding slots and providing a limited degree of freedom for universal motion.

In witness whereof, I hereunto subscribe my name this 28th day of February, 1929.
